UNITED STATES PATENT OFFICE

2,584,542

APPARATUS FOR MAKING TUBULAR
PAPER CONTAINERS

John Henry Brown, Jr., Sands Point, N. Y., assignor to Lily-Tulip Cup Corporation, New York, N. Y., a corporation of Delaware

Application April 2, 1947, Serial No. 738,827

18 Claims. (Cl. 93—36.1)

1

This invention relates to a method of and apparatus for making two-piece paper or the like containers such as cups, and more especially such containers where thermoplastic adhesive is employed for the seams.

It has long been well known to join or unite paper or the like material with thermoplastic adhesives, under heat and pressure; and that such an adhesive seam has characteristics making it desirable for withstanding certain liquids and temperatures. However, it has not been found possible heretofore to utilize such knowledge in practical mass production operations applicable to the manufacture of individual service or relatively cheap products, such as drinking cups.

An object of this invention is to provide a method of economically making two-piece paper containers wherein the seams or joints are thermoplastic.

Another object of the invention is to provide apparatus for the rapid and economical manufacture of two-piece paper or the like containers wherein the seams or joints are thermoplastic.

A further object of the invention is to provide an automatic machine for the manufacture of such containers.

Further objects of the invention will more fully appear from the following description taken in connection with the accompanying drawings illustrating by way of example the preferred embodiment of the apparatus used in carrying out the method.

The invention consists in the method herein described and in the novel features, arrangement, construction and combination of parts of the apparatus and means hereinafter described in accordance with certain preferred embodiments thereof, and the invention will be more particularly pointed out in the appended claims.

Referring to the accompanying drawings, in which the same reference characters indicate the same parts in the various views:

Fig. 1 (Sheet 1) is a plan view of the machine, with bottom blank forming mechanism and other parts omitted for clarity;

Fig. 2 (Sheet 2) is a vertical sectional view taken in general along line 2—2 of Fig. 1;

in vertical section showing the bottom seam resulting from the operation at station IV;

Fig. 24 (Sheet 16) is a vertical sectional view taken on line O-24 of Fig. 1 (station V) showing the bottom squeezing mechanism;

Fig. 25 (Sheet 9) is a side elevation of an actuating cam drive for the bottom squeezing mechanism of Fig. 24;

Fig. 26 (Sheet 17) is a vertical sectional view taken on line O-26 of Fig. 1 (station VII) showing the cup push-out to beader mechanism;

Fig. 27 (Sheet 18) is a vertical sectional view taken on line 27-27 of Fig. 1 (stations VIIA and VIIIB) showing the cup rim beading and discharge; and

Fig. 27a is a vertical sectional view showing further details of parts shown in Fig. 27.

GENERAL OUTLINE

In general the invention contemplates the making of paper or the like containers, such as paper drinking cups, from body blanks provided on one surface with a marginal stripe or band of thermoplastic adhesive disposed along one end and the bottom edge of said blank; said adhesive coating is preferably printed on the blank and is allowed to dry or become non-tacky prior to the feeding of the blanks to the apparatus for making the cups. Preferably, said adhesive stripes are applied in proper register on a web of material which is also given an over-all heat resistant coating. In the present embodiment of the invention the web is fed forward and the blanks are successively punched from the vertically disposed web by blanking dies.

The blanks are successively fed by a pusher in a direction normal to the axis of a shell or receptacle which forms part of a blank prefolding mechanism which is located in a fixed position at what will be termed station I (Fig. 1). Other instrumentalities for completing the formation of the body of the cup, and supplying and assembling therewith the bottom of the cup, are arranged in a circular path about a common center O with their respective axes in fixed position at respective of a plurality of stations which will be designated II, III, IV, V, VI and VII, and an idle station designated VIII is included in the circular series. Beading and discharge stations VIIA and VIIIB are disposed in a second circular path about an axis offset from the axis of station VII for forming a beaded lip on the cup and for discharging the finished cup to suitable stacking mechanism. A plurality of female body forming dies, equal in number to said first eight stations, are supported on a common carrier or turret mounted for intermittent rotation about the vertical axis at O and are arranged to fall into successive register with respective of said stations as the carrier is intermittently rotated in a clockwise direction as viewed in Fig. 1. The female dies act as holders for the cups during fabrication.

Relative to the usual frustro-conical receptacles with which the invention is primarily concerned, the body blanks of which are of general arch form, I have found that when a blank is engaged intermediate its ends and fed in a direction transverse to its plane and into a prefolding receptacle of generally circular or other substantially closed cross-section the opposite ends adjacent the upper or greater arcuate dimension of the blank have an inherent tendency to drop downwardly in overlapping relation and in such prefolded position the blank may then be delivered from said pre-

folding shell into a female die. However, where the angle of taper of the receptacle is slight, as in soda cups (Fig. 9) where the arch of the blank is relatively shallow, I have found it preferable to use a tapered prefolding receptacle and a tucking finger therein to cause a progressive increase in the overlap of the opposite ends as the blank is fed toward and through the smaller end of the tapered shell and into the female die. In the present illustrative embodiment apparatus is shown for making the soda cup type of container where a tapered prefolding shell is shown as preferable; but it is to be understood that in its broader aspects the invention is not thus limited.

A blank is first fed into said prefolding receptacle in a direction transverse to its axis and is then moved axially thereof to prefold the blank to bring its opposite marginal ends in proper overlapped position. The prefolded blank passes through the lower open end of said receptacle and into one of said plurality of female body forming dies which is then positioned in axial alignment with said prefolding receptacle at station I. The carrier is then moved step by step so that the female die bearing the preformed blank is progressively moved into axial alignment with successive of said stations at each of which it is held at rest while progressive steps in the manufacture of said cup are preformed in the manner now to be briefly outlined: it being noted that after a given female die has passed through the operations in completing the formation of the body and the cup is discharged therefrom said female die is moved back to station I for receiving another blank and the cycle is repeated. It is further noted that the female dies are suitably heated in zones corresponding to the adhesive seams and provision is also made for controlling the temperature at these zones so as to prevent delamination of the joints during certain stages of operation. In general, male dies and other instrumentalities which cooperate with the female dies at respective stations are located at fixed axes for movement in an axial direction into cooperative engagement with the cups or parts thereof during the various stages of manufacture.

At station II the female die bearing the pre-folded body blank is disposed in axial register with a cooperating male die or plunger mandrel which reciprocates axially to press the body blank into form between said male and female dies; heat supplied adjacent the adhesive stripe having softened the same to form the side wall adhesive joint or seam.

At station III the side wall is disposed in suitable register with bottom forming mechanism where a flanged bottom is inserted within the body, from the upper open end, with the flange of the bottom extending downwardly and positioned adjacent the lower marginal edge of the cup body member. The lower marginal edge of the body is then spun or folded over said downwardly extending flange of the bottom member. In the present embodiment, the bottom member which is supplied at this station is punched from a continuous strip of stock and is drawn to flanged shape and the formed bottom is fed laterally into axial alignment where it is engaged by the lower end of a cooperating positioning plunger on which it is held by suction and the plunger reciprocates downwardly to evenly seat the bottom in the formed body disposed within the female die and when the bottom is properly located a suitable spinning die is moved upwardly against the lower edge of the body to fold the same upwardly

interiorly of the downwardly extending flange of the bottom member.

At station IV the bottom of the partly finished cup is positioned in axial alignment with a male die or mandrel which moves downwardly to firmly hold the cup in its female die and an axially aligned bottom rolling mechanism reciprocates upwardly and serves to iron the cooperating portions of the body member and bottom member into more intimate engagement. At station V the cup is brought into axial alignment with a similar male die, which moves downwardly as above described, and with an expandable plug which is first moved upwardly into engagement with the bottom of the cup which is firmly held by the male die, and the plug is then expanded to squeeze or press the cooperating portions of the body and bottom member into intimate contact and final form.

At station VI identical instrumentalities as above described with reference to station V may be optionally employed or this station may be utilized as a dwell station, depending upon the character of stock being used for the cup, etc. For the sake of simplicity this extra squeezing operation is omitted from the present embodiment and station VI is merely supplied with a male die.

It is noted that at stations II, V and VI a cooling medium such as water is passed through the male die to cool the same and prevent undue heating of the paper stock which would inhibit the adherence of the parts being cemented or cause delamination of the parts.

At station VII the cup is withdrawn from its forming die and is complete except for the rolling of the rim. Upon its withdrawal from the forming die at station VII the cup is horizontally moved to station VIIA where the lip beading operation is performed and the cup is then moved horizontally to station VII B where it is discharged to suitable stacking mechanism. During the interval that the cup is moved through the beading station and is being discharged the female die from which it was removed has progressed to idle station VIII and from there progresses to station I to receive the next prefolded blank.

Supporting structure and main drive

Referring more particularly to Figs. 1, 2 and 3: the supporting frame of the machine is designated in general as 30 and comprises a main base 31 (Fig. 2), laterally spaced pedestal plates or side panels 32-33 rigidly secured thereto and extending upwardly therefrom, a table plate 34 rigidly secured on the upper face of said side panels 32-33 and a laterally disposed cross-bar 35 rigidly secured at its ends to the side panels 32-33 and disposed in a vertical direction intermediate the base 31 and table 34 (Fig. 2).

A main turret journal 36 of relatively massive dimensions is rigidly secured to the table 34 as by screws 37 (see also Fig. 24) and is provided with an axial bore through which passes a turret shaft 38 which is rotatably journaled in an axial and radial thrust ballbearing 39 and is radially centered at its lower end by a bearing ring 40 (Fig. 24). The upper end of the shaft is provided with an enlarged head 41 rigidly secured thereto for rotation therewith. A horizontal turret table 42 is rigidly supported on the head 41 to which it is clamped by a cooperating head 43 and screws such as 44. An upper shaft extension 45 is disposed in axial alignment with and rigidly secured to the

shaft 38 by means of the head 43. The upper end of the shaft 45 is suitably journaled in a bracket 46 which is rigidly secured to a top plate 47 (Figs. 1 and 2) which is rigidly supported on three posts 48, 49, and 50 whose lower ends are rigidly mounted on the table 34 (Figs. 2, 3 and 24).

Referring more particularly to Figs. 2, 3 and 12: the turret plate 42 carries rigidly secured thereto a plurality of female dies (in the present embodiment 8 in number) designated in general as F provided with suitable securing means such as flanges 51 and screws such as 52 in threaded engagement with the table 42. Each of the dies F is provided with a steam jacket comprising a vertical passage 53 which is disposed so as to correspond with the location of the vertical adhesive seam of the cup to be made and a peripheral passage 54 which is disposed adjacent to the lower end of the die in the vicinity of the lower adhesive seam of the cup to be formed. The upper end of the passage 53 is in communication with one end of an inlet pipe 55 whose other end is in communication with a passage 56 provided in the turret axle head 43; and the lower passage 54 is in communication with one end of an outlet pipe 57 whose other end is in communication with a passage 58 provided in the turret axle head 41. All of the passages 56 are in communication with a central chamber 59 which is in communication through an axial bore 60 with a steam inlet pipe 61 (Fig. 2) which serves to supply steam from a suitable source (not shown). Similarly, all of the passages 58 are in communication with an annular axially extending passage 62 whose lower end is in communication with a steam outlet pipe 63 which returns the steam to the suitable source. It will thus be seen that each of the eight female dies F is continuously furnished with a supply of steam.

40 A drive train for the turret will now be described, referring more particularly to Figs. 4, 2 and 16. A horizontal drive shaft 64 is suitably journaled in blocks 65-66 which are secured to respective of the end frame panels 32-33 (see also Fig. 21). The shaft 64 carries a gear 67 which is driven by a suitable source of power indicated by the spur gear 68 carried on the end of shaft 69, as shown in broken lines. A bevel gear 70 is fixed to the shaft 64 and is in driving mesh with a cooperating bevel gear 71 fixed to the lower end of a vertical shaft 72, the lower end of which is journaled in a bracket 73 rigidly secured to the supporting frame 30; and the thrust of the bevel gears 70-71 in a horizontal direction is provided for a ballbearing 74 journaled in a supporting bracket 75 which is also rigidly secured to the supporting frame 30. The shaft 72 (Fig. 16) carries secured thereto a Geneva spur 76 provided with a roller 77 (see also Fig. 5) which is in driving engagement with a Geneva wheel 78 provided with eight driven teeth for engagement by the roller 77 and intervening dwell sectors serving to lock the turret during dwell periods. The Geneva wheel 78 is secured to the turret shaft 38 (Fig. 2) by means of a hub 78'. It will thus be seen that the main drive shaft 64 rotates the vertical drive shaft 72 which, by means of the Geneva gear, causes the shaft 38 to rotate intermittently. This causes a corresponding intermittent rotation of the turret table 42 and therefore moves the respective female dies F successively into position at the stations I-VIII in a circular path about the common center which coincides with the axis of shaft 38, designated in the drawing (Figs. 1 and 3) as O. The dwell or period of rest between the

intermittent movements of the turret corresponds to the working periods at the various stations.

Body blank forming

Referring more particularly to Figs. 1, 2 and 6; the mechanism will now be described for punching the cup body blanks from a web of material designated W. This mechanism is supported on vertical standards 79-79' rigidly mounted on the table 34 and forming a part of the frame of the machine. A transversely extending plate 80 is rigidly secured to the uprights 75-76 and serves also as a matrix or female die plate, as will be more particularly pointed out following. A feed drum D is suitably journaled in the upwardly extending ends of the side plates 78-79' (Fig. 1) and is provided with feed pins d for engaging marginal feed holes in the web W. The right hand end of the feed drum axle (Fig. 1) extends outwardly beyond the frame member 78 and carries rigidly secured thereto (see also Fig. 6) a feed ratchet 81 and a locking ratchet 82. The feed ratchet 81 is adapted to be engaged by a feeding pawl 83 mounted on a feed arm 84 and biased to feed position by a spring 85. The feed arm 84 is rotatably journaled on the drum axle and is pivotally connected at 86 to an eccentric rod 87 carrying at its lower end an eccentric ring 88 which is in operative engagement with an eccentric 89 secured to the drive shaft 64 (see also Fig. 4). The locking ratchet 82 is engageable by a locking pawl 90 (Fig. 6) which is pivotally mounted on the side plate 79 and which is biased to locking position by a suitable spring 91 and is moved to releasing position by a roller 92 mounted on a downward extension of the feed arm 84. The parts being so constructed and arranged that as the feeding pawl 83 is moving on its feed stroke against one of the teeth of feed ratchet 81 the locking pawl 90 rides on a smooth sector of the locking ratchet 82 and comes into engagement with one of the locking teeth at the end of an increment of rotation of the feed drum D; the cam roller 92 serving to release the pawl 90 from locking engagement immediately prior to the commencement of the next increment of rotation of the drum. The web W is fed to the feed drum D from a suitable supply roll (not shown) over an idle roller 93 and under an idle roller 94. In passing from the drum D the web feeds beneath the resilient spring fingers 95 and is guided vertically downwardly between said fingers 95 and a rearwardly spaced guide plate 96 so as to be guided slightly to the rear of and be centered laterally relative to the vertical matrix plate 80 (Figs. 3 and 7).

The matrix plate 80 is provided with an aperture 97 conforming to the contour of a blank such as B (Fig. 9) bearing an adhesive stripe printed on the rear face thereof so as to form an end stripe a and a bottom stripe a'. As previously explained, the adhesive employed is thermoplastic and is in a dry or non-tacky condition when fed to the machine. A punch die 98 complementary to the matrix 80 is mounted on a carrier plate 99 (Figs. 3 and 7) which is provided with rigidly attached bosses such as 100 through which pass four supporting studs such as 101 so as to accurately maintain the punch and matrix in proper operative register. To the back of the supporting plate 99 are pivotally secured a pair of toggle links 102 whose opposite ends are pivotally secured to a pair of toggle arms 103 rigidly secured to a cross shaft 104, the left hand side of which (as viewed in Fig. 3) carries secured there-

to a crank arm 105 whose other end is pivotally connected to an eccentric rod 106 (Fig. 2) provided with an eccentric ring 107 operatively engaging an eccentric 108 secured to and driven by the drive shaft 64 (see also Fig. 4). The punching die 98 is supplied with a clamp frame 109 (Figs. 7 and 11) which is urged outwardly by suitable compression springs such as 110 carried on dowel pins such as 111 which freely pass through the frame 109 and are rigidly supported by the plate 99. Accordingly, as the punch die 98 is moved forward the web W is clamped between the member 109 and the inner face of die plate 80 to thereby hold the web in registered position while the dies 98 and 80 punch a body blank from the web W.

The plate 99 is also provided with a pair of bushings such as 112 in which are slidably disposed a pair of push rods 113, the forward ends of which pass through the male die 98 and carry secured on their outer ends a pusher plate 114 provided with a rubber or the like resilient pad 115. The rearwardly extending ends of the push rods 113 slidably pass through a block 116 which is positively held in a rearward direction by nuts such as 117 threadingly engaging the ends of the rods 113 and yieldably held in the opposite direction by helical coil springs 118 whose inner ends are anchored by collars 119. The block 116 is pivotally connected, as at 120 to the upper end of a crank arm 121 (see also Fig. 2) which is pivotally mounted at 122 on a bracket 123 rigidly secured to the table 34 and whose opposite end is pivotally connected as at 124 to the rod 125 whose lower end is pivotally attached at 126 to one end of a cam crank 127 which is pivotally mounted at 128 on a bracket 129 rigidly secured to the base 31. The other end of the cam crank 127 (Fig. 8) carries a cam roller 130 which is in driven engagement with a cam 131 secured to and driven by the drive shaft 64 (see also Fig. 4). The parts are so constructed and arranged that after the die 98 has moved forward to punch the blank B from the web W the cam 131 operates the mechanism above described to move the pusher head forward, carrying with it the body blank B.

Referring particularly to Figs. 2, 7 and 10 it will be noted that the matrix plate 80 also carries rigidly secured to the forward face thereof of a receptacle or prefolding shell 140 having a closed top or cover 141 and an open bottom 142. The peripheral inner walls of the shell 140 are tapered downwardly and inwardly and the front face adjacent the plate 77 is provided with a narrow slot-like mouth or opening 144 (Figs. 7, 10 and 11) extending in a vertical direction from a point slightly above the uppermost edge of the opening in the matrix 80 to slightly below the lowermost edge thereof. The mouth 144 is provided with side walls or lips which flare outwardly in a direction from mouth 144 toward matrix 80, as more clearly shown in Fig. 11. Immediately below the bottommost point of the die opening in matrix 80 a block 145 is rigidly secured to the body of the shell 140, as by screws 146 and the inner face of this block extends in a lateral direction slightly beyond the slot-like mouth or opening 144 and is provided with a tucker finger 147. The cover 141 of the shell 140 is provided with a journal hub 148 in which is slidably disposed a rod 149 carrying rigidly secured at its inwardly extending lower end a spider 150 provided with four fingers such as 151, 152, 153 and 154 which are slidably disposed in

corresponding grooves such as 155 formed in the side wall of the receptacle or shell 140. The axis of the shell 140, which coincides with the axis of the vertical rod 149 is in axial alignment with a female die or cup holder F when the same is in register at rest at station I. Means for moving the rod 149 axially so as to reciprocate the spider 150 will now be described, it first being noted that the timing of this reciprocation is such that as the pusher 114 feeds the blank into the shell 140 (Fig. 10) the narrow pusher 114 engages only a relatively narrow zone of the blank B and the laterally extending ends of the blank spring outwardly as they are fed through the inner slot-like opening of the mouth 144 so that the end of the blank bearing the adhesive strip A falls behind the tucker finger 147 as the pusher 114 is withdrawn rearwardly and the spider 150 pushes the blank downwardly along the inwardly tapering side walls of the shell 140. It will thus be seen that the blank is fed into the shell in a direction normal to its axis and is then fed in an axial direction to cause the blank to be prefolded with the edge bearing the interior coating a disposed behind the opposite edge of the blank; and as the spider head 150 continues to move downwardly, at which time the pusher head 114 has been moved to its retracted position, the preformed blank is disposed in one of the female dies F then at station I with the adhesive stripe a and the inner overlapping opposite end of the blank in axial alignment opposite the stem jacket 53. The blank is positioned in proper vertical register within the female die F by means of a stop plate 132 (Figs. 7 and 2) supported on a vertical web 133 rigidly secured to the table 34. The plate 132 is spaced below the bottom of the holder F a distance about one-half the width of the adhesive stripe a'.

Referring more particularly to Figs. 1 and 2, a mandrel head 155 is slidably mounted on the vertical shaft 45 and the posts 48, 49 and 50 (see also Fig. 12) and this head serves to carry the mandrels or male dies and other instrumentalities which are permanently disposed at respective of the stations for movement downwardly into cooperative engagement within the female dies F as they are brought into axial alignment with the various stations. The head 155 is provided with a spool 156 having upper and lower flanges between which are disposed a pair of rollers 157 carried on bifurcated ends formed on the inner end of an arm 158 pivotally mounted at 159 on an upwardly extending portion of the upper plate 47 of the main frame and whose outer end is pivoted at 160 to the upper end of the rod 161 whose lower end is pivoted at 162 to the outer end of a cam lever 163 pivotally mounted on a bracket 164 rigidly attached to the base 31 and whose inner end (Fig. 13) carries a cam roller 165 in driven engagement with a cam 166 secured to and driven by the drive shaft 64. It is to be understood that the cam 166, through the driving connections above described, moves the head 155 downwardly when the turret 42 has come to rest with the respective female dies F in register at the various stations and the head 155 is moved upwardly before the turret is again rotated an increment of movement. The prefolding rod 149, above described, carries at its upper end a flanged spool 167 which is engaged by a roller 168 carried on the end of a lever 169 (see Figs. 1 and 2) whose opposite end is pivotally connected to a

post 170 rigidly mounted on the upper table bracket 47 and the lever 169 is pivotally attached intermediate its ends to a link 171 whose lower end is pivotally attached to the vertically movable head 155, whereby upon reciprocation of the head 155 the prefolding pusher rod 149 is reciprocated vertically in proper timed relation.

Station II

Referring more particularly to Figs. 12 and 1; the vertically reciprocable mandrel head 155 is provided with a bushing 175 in which is slidably disposed a shaft 176 carrying at its lower end rigidly secured thereto a male die or mandrel 177 designated in general as 177 and comprising a body or plug 178 so shaped as to conform to the interior of the cup to be made so that a body blank engaged between the male die 177 and the female die F in cooperative register therewith will be formed into a cup body. A ring plate 179 depends from an upper flange 179 rigidly formed with the body of die 177 by means of a plurality of bolts such as 172 which pass freely through the flange 179 and have their lower ends secured to a stripper ring 178; springs such as 172' serving to resiliently urge said ring downwardly so as to yieldably engage the upper edge of a cup blank B. A helical compression spring 173 is interposed between the spider head 155 and a washer 173' which engages the upper end of the male die 177 so as to provide a predetermined pressure between the female and male dies as the spider head is moved downwardly. The stem or shaft 176 of the male die is provided with an axial bore 174 in which is disposed a tube 134 whose lower end extends downwardly into a cavity 135 provided in said male die and a suitable flexible tube 136 is secured to the upper end of stem 176 in communication with the bore 174 and tube 134. The cavity 135 is provided with an outlet 137 which is suitably connected with a tube or flexible hose (not shown) to provide a suitable outlet for a cooling medium such as water which is introduced through the tube 136 and outwardly at the lower end of the tube 134 to thereby cause the cooling medium to circulate through the male die 177 for the purpose of preventing delamination of the adhesive joint. It will be seen that the plate 132, previously described, extends past the bottom of the female die F at this station II so as to hold the body blank in proper vertical position.

Station III

At station III the bottom of the cup body is placed in position within the previously formed body. In the preferred embodiment of the invention the cup bottom is punched from a strip of material, drawn to flanged shape, placed in proper position within the cup body and the lower marginal edge of the body is turned or rolled somewhat loosely over the downwardly extending flange. The mechanism for forming the cup bottom first will be described, with particular reference to Figs. 3, 14-16, inclusive. The bottom forming mechanism is designated in general as 189 and is supported on a frame 181 rigidly secured to the table 34. A pair of idle rollers 182 are suitably mounted for guiding the strip between guide plates 183 from whence they pass between a feed roller 184 and a co-operating pressure roller 185. The feed roller is mounted on a shaft 186 (Figs. 14 and 15) which carries a feed ratchet 187 and a locking ratchet 188 is secured thereto. The feed ratchet 187 is adapted to be driven intermittently by a pawl

189 pivotally carried on an arm 190 which is journaled on shaft 186 and is pivotally attached at 191 to a driving rod 192 (Fig. 16) which is suitably pivotally connected to lever 193 pivotally mounted on a bracket 194 which is rigidly secured to the under side of table 34 and the other end of the arm 193 (not shown) is connected by means of the usual rod and eccentric ring 193' to a driving eccentric 195 (Fig. 4). The locking pawl 196 (Fig. 15) is pivotally mounted at 197 and is actuated to open position by abutment of a nut 198 and to closed position by a suitably anchored tension spring 196'; the parts being so constructed and arranged that during the intervals of feeding movement of the roller 184 the pawl 196 is in released position and during the intervals between such feeding movement the roller is in locked position. Cooperating male and female punching dies 200 and 201 respectively are disposed in position to punch bottom blanks from a strip S (Fig. 3) and the male die is axially reciprocated by suitable engagement with the inner end of a lever 202 pivotally mounted at 203 to the table 34 and pivotally connected at its outer end 204 to an actuating rod 205. The lower end (Fig. 4) carries an eccentric ring in driven engagement with an eccentric 206 secured to and driven by the shaft 64. A cooperating drawing ring 207 (Fig. 14) is disposed in alignment with the aforesaid punching dies and mounted for cooperative association therewith is a drawing plunger 208 provided with an actuating rod 209 which (Fig. 16) is pivotally connected at 210 to a rod 211 whose lower end is pivotally connected at 212 to one end of a cam arm 213 pivotally mounted on a bracket 214 rigidly secured to the base 31; and the other end of the arm 213 carries a cam roller 215 in operative engagement with an actuating cam 216 secured to and driven by the shaft 64. The parts are so constructed and arranged that immediately after the bottom blank is punched from the sheet the drawing dies 207-208 draw the blanks so as to form a downwardly extending peripheral flange and the formed bottom is moved upwardly where it is engaged by suitable means to transfer it laterally into axial alignment at station III in the manner to be more particularly pointed out following.

Referring more particularly to Figs. 14, 3, 16 and 17: as the formed cup bottom B' is moved to its uppermost position it is engaged in a U-shaped transfer holder or head 220 which is rigidly secured to a transfer arm 221 mounted on a vertically extending shaft 222 (Fig. 16) journaled in a standard 223 which is rigidly secured to the upper face of the table 34. The lower end of the shaft 222 carries fixed thereto an arm 222' (see also Fig. 17) to one end of which is pivotally connected a rod 224 whose outer end extends through a trunnion 225 which is resiliently centered between compression springs 226 and 227 whose oppositely disposed ends are anchored by cooperating nuts in threaded engagement on the rod 224. The trunnion 225 is journaled in a cam arm 228 which is pivotally supported on a pin 229 secured to the table 34 (Fig. 16). A cam roller 230 is pivotally secured intermediate the ends of the lever 228 and is in operative engagement with a cam 231 which is secured to and driven by the vertical drive shaft 72 previously described. The other end of the arm 222', which is pivoted about axis 222, is provided with a stop screw 232 which is adjusted and located in such position as to bring the holder 220

on the end of operating arm 221, at the forward end of its stroke, into axial registration with the female die F positioned at station III. The holder 220 is brought into register with the punching and drawing dies (Figs 14 and 3) by means of a stop plate 233. It will be understood that the parts are constructed and arranged so that the formed cup bottom, designated B' in Fig. 14, is transferred laterally from a point where it is completed into axial alignment over the formed cup body (Fig. 3) disposed in the female die F at station III; it being noted that the supporting plate disposed beneath stations I and II terminated between stations II and III so as not to interfere with the bottom curling operation hereinafter to be described.

Referring more particularly to Fig. 18: mechanism will be described for receiving the formed bottom from the feeding head 220 and for moving the formed bottom downwardly into position within the formed cup body. A plunger head 234 is provided with a stem or shaft 235 which is slidably journaled for vertical movement in the head 155, being provided with limit washers such as 236-236'. A spring 237 is interposed between the carrier head 155 and the washer 236' to urge the plunger head 234 downwardly. The plunger shaft 235 is provided with a fixed flange 238 which carries a plurality of screws 239 whose stems are slidably disposed in the flange 238 and whose lower ends carry fixed thereto a movable ring plate 240 which is resiliently urged downwardly by springs such as 241. The head 234 and associated parts provide in effect a male die or mandrel. The stem 235 is provided with an axial bore 242 whose upper end is in communication with a suction hose 243. The bottom face of the plunger head 234 in its upper position is disposed in a horizontal plane adjacent to but slightly above the horizontal plane in which the formed cup bottom B' is delivered by the transfer head 220 over the axis at station III and shortly prior to the delivery of the formed bottom to the plunger head 234 suction is supplied through the axial bore 242 by means of the suction hose 243 whose other end (Fig. 4) is connected through a suction valve 244 to a suitable source of suction. The valve 244 is actuated in timed relation to the cycle of operations by means of a cam 245 which is secured to and driven by the shaft 64. After suction has been supplied to hold the cup bottom on the lower face of plunger 234, as indicated in Fig. 18, the feed arm 220 moves on its back stroke and disengages the formed cup bottom which passes outwardly through the open jaws of the holder 220 (Fig. 3) and thereafter the head 155 (Fig. 18) moves downwardly to feed the cup bottom into the proper horizontal position within the formed cup body. In this position the lower edge of the downwardly extending flange of the cup bottom is disposed above the lower edge of the cup body to provide a sufficient marginal edge to be turned interiorly of the bottom flange by the means now to be described.

Referring more particularly to Figs. 19 and 20: a spinner head 246 is mounted on the upper end of a vertically disposed shaft 247 which is rotatably journaled in combined axial and radial thrust bearings 248 and 249 which are suitably mounted in a journal 250 which is axially slidably disposed in bearings 251 and 252 which are rigidly secured to the table 34 as by screws such as 254: a suitable spline key 255 being provided between the bearing 251 and the vertically movable sleeve

250 to permit relative axial movement while preventing relative rotative movement. The journal sleeve 250 is provided with a groove 256 in which is engaged a roller 257 carried on the end of an arm 258 which is pivotally mounted at 259 on a supporting arm 260 integrally formed with the bearing member 252. The outer end of the arm 258 is pivotally attached at 261 to the upper end of a rod 262 whose lower end is pivotally attached to one end of a cam lever 263 pivotally mounted at 264 on a bracket 265 which is rigidly secured to the cross bar 35; and the opposite end of arm 263 carries a cam roller 266 which is in operative engagement with a cam 267 secured to and driven by the shaft 64 (see also Fig. 4). Tension spring 268 has its lower end secured to the rod 262 and its upper end anchored to the table 34 so as to urge the curling or spinning head 246 in a downward direction. The vertical axis of the spinning head 246 and its drive shaft 247 coincides with the axis of a female die F at rest at station III. The spinning head 246 is provided with the usual grooved pins such as 269 and the grooves are disposed in register with an annular groove 270 provided in the body of head 246. The groove 270 is so constructed and arranged as to conform to the lower marginal edge of the formed cup body, so as to curl or spin the same in the manner well understood by those skilled in the art when the curling die 246 is rotated and moved axially. To provide for rotation of the curling die 246, the lower end of its drive shaft 247 carries secured thereto a pulley 271 which is driven by a belt (Fig. 1) indicated by the broken lines 272 and driven from a pulley 273 secured to the shaft 274 of an electrical motor 275 which is rigidly mounted on the end panel 32. The parts are so constructed and arranged that upon delivery of the formed bottom by the plunger 234 and while the plunger is still positioned downwardly to the limit provided by the plate 249 and co-operating flange 238 the cam 267 acts through the mechanism previously described to raise the spinning head 246 so as to curl the lower marginal edge of the cup body inwardly and upwardly interiorly of the inner face of the flange of the cup bottom; it being understood that as the curling or spinning head 246 is moved upwardly it is continuously rotated by means of the pulley 271 and its interconnecting driving means. When the spinning operation is completed the head 246 is reciprocated downwardly, the suction has been cut off from the plunger 234 and the plunger is moved upwardly to its raised position by the upward reciprocation of the carrying head 155. It will be understood that this curling operation more or less loosely disposes the inturned edge of the cup body in position for the succeeding operations now to be described.

Station IV

At station IV (Figs. 1 and 3) the inturned lower marginal edge of the cup body is ironed or rolled into more intimate engagement with the down-turned flange by the mechanism now to be described with reference to Figs. 21 and 22. An ironing head or roller 280 (Fig. 22) is mounted for vertical movement in a direction axially of the female die F positioned at station IV, for eccentric movement with respect to said axis and for rotation. The ironing roller 280 is journaled on suitable bearings 281 supported on a stud shaft 282 which is fixed at its lower end to a cross head 283 slidably disposed in a housing 284 which is rigidly secured to a sleeve shaft 285 journaled

in an upper ballbearing 286 and a lower ballbearing 287 carried in a surrounding sleeve 288 which is supported for axial sliding movement in a bearing 289 secured to the table 34 by screws such as 290. The sleeve 288 is provided with a groove or recess in which is disposed a roller 291 whose axle 292 is pivotally journaled in one end of an arm 293 whose other end (Fig. 21) is pivotally connected at 294 to the upper end of a rod 295 whose lower end is pivotally connected to one end of the lever 296 whose other end carries a roller (not shown) in driven engagement with a cam 297 (Fig. 4) secured to and driven by the shaft 64. This arrangement providing for vertical movement of the ironing roller 280 with respect to the female die F.

The inner sleeve shaft 285 (Fig. 22) carries fixed to its lower end a drive pulley 298 which is in driven engagement (Fig. 1) with a belt 299 driven by a pulley 300 secured to the shaft 274 of the motor 275 thus providing for rotation of the shaft sleeve 285. The eccentric movement of the ironing roller 280 is effected (Fig. 22) by the mechanism now to be described. A toggle link 301 is pivotally secured at its upper end to the cross-head 283 and its lower end is engaged in a recess 302 provided in the upper end of a plunger 303 provided with a bore in which is slidably disposed a rod 304 having a transversely extending pin engaged within a slot 305 formed in the plunger 303 to thereby provide for relative axial movement while preventing relative rotative movement between the piston 303 and the rod 304. The rod 304 is provided with a shoulder between which and the piston 303 is disposed a compression spring 306. In order to prevent relative rotative movement of the rod 304 and the piston 303 with respect to the sleeve shaft 285 the rod 304 is provided near its lower end with a slot 307 in which is disposed a pin 308 fixed to the drive sleeve 285, whereby the rod 304 is rotated with the sleeve 285. The lower end of the rod 304 is suitably journaled in a roller bearing 309 carried by a block 310 to which is pivotally attached by means of a link 311 one end of a lever 312 which is pivotally mounted on a relatively rigid bracket 312 and whose other end is pivotally connected to an upper end of a rod 313 whose lower end is pivotally connected to a cam lever 314 pivoted about an intermediate axis 315 and carrying at its opposite end a cam roller 316 operatively engaged by an actuating cam 317 secured to and driven by the shaft 64 (see also Fig. 4). It will thus be seen that the cam 317 actuates the linkage above described to lift the rod 304 which in turn through the resilient spring drive 306 raises the piston 303, causing the angular movement of the eccentric link 301 about its fixed pivot on the cross-head 283 to thereby move the cross-head 283 which in turn moves the stud axle 282 and the ironing roller 280 in a radial direction outwardly from the concentric position where they are normally held by means of a spring 283'.

From the foregoing it will be understood that the mechanism just described operates in such timed relation that after the female die F (Fig. 22) is moved into axial alignment at station IV carrying with it the partly assembled cup body B and bottom B', a male die or mandrel designated in general as 177a (identical with the mandrel 177 previously described at station II, Fig. 12) is moved into seated position and the ironing roller 280 is moved upwardly until its flange strikes the lower face of the female die F,

at which time its central portion is disposed beneath the bottom B' and within the inturned bottom flange of the cup, the eccentric action of the ironing roller 280 then takes place during the continuous rotation of the housing 284 thus revolving the eccentrically disposed ironing roller 280 which freely rotates about its stud axle 282 during its revolution about the axis of the cup. This serves to iron the parts of the cup to the approximate position shown in Fig. 23. It is noted that at this station the male die 177a is not supplied with cooling medium, as was the case at station II.

Station V

At this station the interlocking cup parts B—B' as shown in Fig. 23 are squeezed into more intimate adhesive engagement by the mechanism now to be described. Referring more particularly to Figs. 2 and 24; it will be seen that an expanding plug designated in general as 320 is disposed beneath one of the female dies F positioned at station V and in axial alignment therewith; and a male die or mandrel designated in its entirety as 177b, is disposed above the female die F and in axial alignment with the expanding plug 320. The male die 177b is constructed and arranged exactly in accordance with the male die previously described in connection with station II (see Fig. 12) and is brought into cooperative relationship with the female die F in the manner previously described and as shown in Fig. 24. The expanding plug 320 comprises an expanding head formed of a plurality of segments such as 322 which are resiliently held toward their axial center by a helical peripheral spring 323 and the segments 322 are provided with lower flange portions disposed between a plate 324 and a cooperating flange portion provided on a hub 325 to which the plate is held by suitable screws such as 326; it being understood that the segments are radially movable with respect to the hub 325 and attached plate 324. The hub 325 is slidably journaled on a sleeve 327 which is provided with a flange 328 rigidly secured to the table 34 by screws such as 329. A compression spring 330 surrounds the hub 325 and is interposed between the upper head of said hub and the table 34 so as to resiliently urge the hub and plug 322 carried thereby in an upward direction. A plunger shaft 331 slidably passes through the bearing member 327 and at its upper end carries an expander head 332 which engages correspondingly tapered concentric inner surfaces formed on the segments 322; so that upon upward axial movement of the plunger shaft 331 the expanding plug 320 is first bodily moved upwardly until it engages the bottom face of female die F and then upon continued upward movement of the shaft 331 the expanding head 332 forces the segments 322 outwardly and into squeezing engagement with the inwardly turned marginal edge of the cup body blank to thereby firmly press the inturned edge of the body blank against the inner face of the bottom flange of the cup bottom to seal the adhesive seam under heat and pressure. The vertically movable shaft 331 carries at its lower end a spool 333 (Fig. 2) providing flanges between which is disposed a roller 334 carried on the inner end of an arm 335 which is pivotally mounted on a bracket 336 rigidly secured to the under side of table 34 and the outer end of the arm 335 is pivotally connected to an upper end of rod 337 whose lower end is pivotally connected to one end of the cam arm 338 which is pivotally mounted on a bracket 339 rigidly secured to the

cross bar 35; and the other end of the cam arm 338 (see Fig. 25) is provided with a cam roller 340 in operative engagement with a driving cam 341 which is secured to and driven by the drive shaft 64 (Fig. 4). The parts are so timed that when a female die F is brought to rest at station V the male die 177b is reciprocated downwardly by movement of the carrier head 155, as previously described, and the cup is firmly held between the mandrel 177b and cooperating female die F and thereafter the expanding head 320 operates as above described to firmly squeeze the adhesive seam. As previously pointed out in connection with Fig. 12 (station II) cooling fluid is circulated through the male die to prevent delamination of the adhesive joints.

Station VI

As previously referred to, a male die or mandrel designated in general as 177c (Fig. 1) identical in all respects with the die 177 at station II (Fig. 12) is utilized at station VI, but for purposes of simplicity is not illustrated in detail. At station VI the male die is cooled as at stations II and V. It is further noted that in operating upon certain types of containers or containers made of certain types of paper it may be found desirable to utilize a second expanding plunger at station VI and in such event an expanding plunger constructed and operated in the identical manner as above described with reference to the plunger 320 at station V may be duplicated at station VI, but in the present embodiment such duplication has been omitted for purposes of simplicity.

Station VII

At station VII (Figs. 1 and 3) the cup is ready to be discharged in its completed form except for the rolling of the beaded lip. The mechanism for ejecting the cup from the female die F at station VII first will be described and thereafter the apparatus will be described for applying the beaded edge to the lip of the cup. Referring more particularly to Fig. 26, a female die F is shown at rest at station VII immediately over an axially disposed ejecting plunger designated 345 mounted on an actuating stem or shaft 346 which is slidably journaled in a bearing 347 rigidly secured to the table 34 as by screws 348; the rotation of the head 345 being prevented by a set screw 349 whose inner end is disposed within a groove formed in the outer surface of the stem 346. The stem extends through the bearing 347 and its lower end is provided with a spool 350 between whose flanges is disposed a roller 351 pivotally carried on the outer end of a lever 352 which is pivotally supported on a bracket 353 rigidly secured to the table 34 and whose inner end is pivotally attached to the upper end of a rod 354 whose lower end is pivotally attached to a cam lever 355 pivotally mounted on a bracket 356 rigidly secured to the cross bar 35. The other end of the cam lever 355 being provided with a cam roller 356 in operative engagement with a cam 357 which is secured to and driven by the drive shaft 64 (Fig. 4). The ejector plunger stem 346 has disposed about its lower end a helical compression spring 358 interposed between the spool 350 and a stop washer 359 which is seated on a shoulder provided on the stem 346. The stem 346 is provided with an axial bore 360 whose upper end is in communication with a chamber 361 provided with a plurality of outlet orifices 362; and the lower end of the bore 360 is in communication with a pipe 363 which is con-

nected with a suitable source of compressed air (not shown) by way of a whistle valve 364. The valve 364 is provided with an actuating plunger 365 which is operated by the head of a screw 366 carried by a bracket 367 which is rigidly secured to an adjacent face of the lever 352, and the screw 366 is so adjusted that as the lever 352 moves the stem 346 and the ejection plunger 345 upwardly into engagement with the bottom of a cup to be ejected the actuating plunger 365 opens the valve 364 to cause compressed air to flow upwardly through the bore 360 and outwardly through the orifices 362 to assist in ejecting the cup from the female die F.

Referring more particularly to Figs. 1, 2 and 27: a beading turret 370 (Fig. 1) is fixed to the upper end of a vertical shaft 371 (Figs. 3 and 27) which is slidably disposed in a drive sleeve 372 rotatably journaled in a bearing 373 which is rigidly mounted on the table 34. The shaft 371 is rotatably fixed to its drive sleeve 372 by a key 374 which is seated in a spline-way in shaft 371 to permit its axial movement; the sleeve 372 is also rotatably secured to a driving pinion 375 by means of a key 376 and is rigidly supported at its lower end and held against axial movement by a bracket 377 carried by the cross bar 35. The pinion gear 376 is in driven mesh with a pinion gear 378 (see Fig. 5) mounted on a stub shaft 379 rigidly carried by the bracket 377 and the gear 378 in turn is in driven mesh with a pinion gear 380 journaled on a stub shaft 381 rigidly carried by the bracket 377 and in driven engagement with a ring gear 382 which is rigidly secured to the Geneva gear 78 (see also Fig. 2) by means of screws such as 383 which also serve to attach the Geneva gear 78 to its hub 78'. It will thus be seen that as the Geneva gear is rotated intermittently the ring gear 382 is given a like intermittent movement which is imparted to the drive sleeve 372 and its rotatably connected shaft 371 (Fig. 27) to thereby intermittently rotate the beader mandrel 370.

The shaft 371 carries secured at its lower end a spool 384 provided with the usual flanges between which is disposed a roller 385 carried on one end of a cam lever 386 whose other end is pivotally mounted at 387 on a suitable support (not shown) rigidly mounted on the base 31 and a cam roller 388 is mounted on the lever 386 in driven engagement with a cam 389 secured to and driven by shaft 64 (Fig. 4). The movement so imparted raises and lowers the shaft 371 and beader turret 370 in timed relation to the periods of dwell in the turret's rotative cycle.

Each of the three arms of the turret 370 (Fig. 1) carries a beading die and associated suction plunger for engagement within the body of the cup and this structure will now be described with reference to Fig. 27. A beading die ring 390 is rigidly secured on its stem 391, as by screws 392, and the upper end of stem 391 passes through a bore in the corresponding arm 393 of the turret 370 to which it is secured by a nut 394 in cooperation with a flange 395 formed on the stem 391 and angularly locked by a pin 396. A suction head 397 is slidably carried on the lower end of stem 391 and is held in place by a supporting plate 398, which limits its downward movement on said stem, and is yieldably urged thereagainst by a helical compression spring 399 which provides for relative movement of the suction head toward the beading die ring 390. The suction head is restrained against angular movement about its axis by arms such as 400 depend-

ent from the die 390. The suction head 397 is provided with a radially extending bore 401 which passes through the stem 391 where it is in communication with two downwardly extending passages 402 and 403. The passage 402 passes through the plate 398 on the lower end of the suction head 397; while the passage 403 is plugged at its corresponding lower end by a plug 404 and is in communication with an annular chamber formed in the hub of plunger 397 and from which radially extending passages such as 405 pass outwardly through the outer periphery of plunger 397. The bore 401 is completely closed between the passages 402 and 403 by means of a plug 406 so as to provide two separate passages; one 401—402 for compressed air to be passed outwardly below the head 397 and plate 398, and the other 401—403—405 for suction to be imposed on the outer edge of the head 397. When suction is imposed and compressed air is disconnected the passage 401—402 acts as a bleeder to prevent collapse of the cup while permitting sufficient suction to hold the cup in position on the head 397. The inwardly disposed ends of the bores such as 401 are in permanent communication with a passage provided in the shaft 371 comprising radial bores such as 407, an axial bore 408 and a radial bore 409 which terminates outwardly in the upper end of an annular passage 410 formed between a reduced portion of the shaft 371 and the interior of the drive sleeve 372. The lower end of the annular passage 410 is provided with an inlet opening 411 in continuous communication with an annular passage 411' which is connected to a suitable source of suction by means of a suction tube 412 secured to the bushing 373. Valve plungers such as 413 are disposed in cooperating bores extending transversely of the respective radial bores such as 411 and are held downwardly by cooperating springs such as 414 to leave the bores 401 normally open to the passages 407, etc. The valve plungers are provided with engageable ends such as 415 which are adapted to be engaged successively by an actuating stop 416 when the respective arms are rotatably moved into register therewith and the turret 370 moves downwardly.

It will be understood that each of the turret arms is provided with a beading ring and suction head constructed and arranged as previously described, and for purposes of ready reference these mechanisms will be referred to in general as 391 (Fig. 27), 391a and 391b (Fig. 1). As shown in Fig. 27, 391 is disposed in axial alignment with the beading station VIIA (Fig. 1), 391a is in axial alignment with the discharge or ejection station VIIB and 391b is in axial alignment with station VII where a cup to be beaded is received.

Station VIIA

At station VIIA there is positioned a beading die receptacle 420 provided with an upper die ring 421 which is complementary with the die ring 390 for beading the upper marginal edge of a cup. The receptacle 420 is rigidly mounted on a base 422 secured to the table 34 and provided with a hub 423 in which is slidably mounted a stem 424 provided at its lower end with a suitable adjustable lower limit stop 425 and upper limit stop 426; and whose upper end carries secured thereto a plate disk 427 between which and the hub 423 a helical compression spring 428 is disposed. The beader receptacle 420 is preferably provided with a jacket 429 having inlet and outlet open-

ings 430—431 for circulating a cooling medium such as water.

Station VIIB

At station VIIB where the beaded cups are ejected a hollow post 432 is rigidly mounted on the table 34 and on its upper end carries a compressed air valve and coupling body 433 provided with an axial bore 434 (Fig. 27a) in communication with the interior 435 of said post 432 and with a transvers bore in which is disposed a valve stem 436 integral with a coupling head 437 urged outwardly by a compression spring 438 and limited in such direction by a collar 439.

The stem 436 is provided with a passage 440 extending inwardly from the face of the head 437 to a point short of the bore 434 and thence downwardly parallel to but out of register with bore 434. The parts being so constructed and arranged that upon the head 437 being pushed rearwardly against the spring 438 the passage 440 is placed in communication with the axial bore 435 the lower end of which is in communication with a source of air pressure by way of a hose or pipe 441. The coupling head 437 is so positioned that when an end such as 393 of one of the turret arms is rotatably moved to station VIIB and then moved downwardly it will move the valve head 437 outwardly to open position and the corresponding bore 461 on the turret arm will be in register with the compressed air passage 440.

With the beaded cup in this position it is discharged by said compressed air from the beader turret in a vertically downward direction over a discharge opening 443 (Figs. 27 and 1) in table 34 and is guided by a chute comprising guide wires such as 444 fastened at their upper ends to a ring 445, supported on a post 446 secured to the table 34, and at their lower ends to a yoke 447 secured to table 34. Horizontally disposed stacking rails 448 are provided for receiving cups ejected from the beading turret and a stacking pusher 449 is provided for pushing successive cups into stack formation. The pusher 449 is carried on the upper end of an arm 450 pivotally supported on a bracket 451 mounted on the frame panel 33. The other end of arm 450 is pivotally connected by means of a link 452 to one end of a cam arm 453 pivotally mounted intermediate its ends to bracket 377 and provided at its other end with a cam roller 454 in driven engagement (Fig. 4) with a cam 455 secured to and driven by shaft 64. The pusher 449 is so timed that it engages each cup against its beaded lip as the cups successively reach the stacking rails 448 and pushes it forward into the preceding cup of the stack.

OPERATION

Referring more particularly to Figs. 1 and 2 it is noted that at every revolution of the shaft 64 the turret 42 is given an increment of movement and is locked in fixed position: in the present embodiment the movement takes place through approximately 135° of the shaft 64 and the period of dwell extends approximately for 225°. During the period of dwell the cup holders or female dies F coincide with the axes of the respective stations I—VIII, inclusive.

Station I.—Body blank punching, feeding and prefolding

With a web W passing around the drum D and extending downwardly between the matrix 80 and die punch 98 the drum D is rotated one step (Fig. 6) by the downward movement of the eccentric rod 87 to bring the adhesive stripe

printed on the rear face of the web into accurate register with the punch dies. Thereupon the locking pawl 90 engages the locking ratchet 82 to thereby lock the feed drum; eccentric rod 106 moves downwardly to actuate the toggle link 102 to move the punch die 98 forwardly (Figs. 7 and 10) which first moves the clamping plate 109 forward to clamp the web W between the punch dies 98—80 and thereafter passes the punch 108 through the matrix 80 to punch out the cup body blank B. As soon as the blank is thus cut from the web the lever 121 is actuated by the mechanism previously described to move the pusher head 114 forwardly to feed the blank through the inwardly tapered lips of mouth 144 (Figs. 10-11) into the prefolding shell 140: the resilient face pad 115 frictionally engaging the blank and also being compressible to conform to the downwardly tapered interior wall of the shell 140. As the ends of the blank B are pushed through the relatively narrow vertically extending slot-like opening on the inner end of the mouth 144 the ends spring outwardly to hold the blank within the shell for the time interval during which the pusher 114 moves on its return stroke. The interior face of the block 145 is slightly greater in peripheral extent than the inner slot-like opening of the mouth 144 and therefore as the vertically actuated pusher 150 is moved downwardly by its stem 144 the end of the blank B on which is disposed the stripe a of adhesive material is moved behind the tucker finger 147 (Fig. 11) due to the downwardly and inwardly tapered walls of the shell 140, and similarly the opposite end of the blank B is disposed on the opposite face of the tucker finger 147 in a position overlying the end bearing the adhesive stripe a. This prefolded condition of the blank is indicated in broken lines in Fig. 11. Upon continued downward movement of the pusher head 150 the prefolded blank (Fig. 7) is pushed out of the open lower end of the shell 140 and into one of the cup holders or female dies F which at this time is at rest beneath and in axial alignment with the shell 140. Upon retraction of the pusher head 150 upwardly the turret 42 is given an increment of movement and the holder F bearing the prefolded cup body is brought into axial alignment at station II.

Station II.—Forming cup body

Referring more particularly to Fig. 12: just before the female die F comes to rest at station II the head 155, which carries the mandrels or male dies, commences its downward stroke, by the actuation of rod 161 and related mechanism (Fig. 2), so that by the time that the female die F is brought to rest the mandrel or male die 177 moves within the prefolded cup body B, the resiliently held ring 178 moving the blank downwardly into vertical register with its lower end resting upon the plate 132. The female die F having been heated by steam circulated through the pipes 55—57, the adhesive is softened so that under pressure of the cooperating dies 177 and F the vertical seal is effected. To prevent delamination of the adhesive seam cooling water is circulated through the pipes 183—87. Thus the cup body per se is formed; the mandrel or plug die 177 remaining down to exert pressure on the seam during the major or a substantial part of the dwell of the female die F at station II. The head 155 is then raised to move the male die 177 upwardly beyond the female die F and the turret 42 commences its movement to the next station III.

Station III.—Forming the cup bottom, inserting it in position, and spinning the bottom edge of the body

During the dwell of the female die at station II the bottom forming mechanism 180 (Fig. 3) has punched the bottom blank and drawn the same to flanged form and during the movement of the cup body from station II to station III the bottom transfer mechanism has moved the bottom into axial alignment with station III (Fig. 3) and beneath the plunger head 243 where suction (Fig. 18) is imposed through hose 243 and the axial bore 242 to engage the formed bottom B' on the lower face of plunger head 243 which in effect is part of a modified form of mandrel or male die. As soon as the bottom B' is thus engaged the transfer arm 221 moves outwardly on its return stroke and the mandrel head 155 is moved downwardly to thereby insert the bottom B' within the body B; the ring 240 resiliently pressing the upper edge of the cup into intimate position within the female die F. Shortly before the plunger head 234 reaches the lower end of its stroke the spinning head 276 (Fig. 20) starts to move upwardly and when the bottom B' has reached its lowest position the head 276 is brought into engagement with the lower edge of the cup body to thereby spin the edge interiorly of the flange of the bottom B' for approximately one-half the width of the bottom adhesive stripe a'. This spinning operation is completed and the spinning head commences to move on its return stroke downwardly before the head 155 moves upwardly to remove the male die above the upper edge of female die F. After the male die has cleared its cooperating female die the turret 42 is given its next increment of movement to carry the partly formed cup to station IV.

Station IV

With the partly formed cup and its supporting holder F in axial register and at rest at station IV (Figs. 21-22) the male die 177a is moved downwardly into engagement to clamp the partly finished cup firmly in position in female die F, in a manner similar to that previously described with respect to station II and the bottom roller 280 is moved up into operative engagement and is then moved to an eccentric position where it is caused to rotate about its stud axis 282 while being revolved about the axis of its drive pulley 298, thereby rolling or ironing the inturned marginal bottom of the cup body into intimate adhesive engagement with the interior of the bottom flange. This rolling operation is continued during the period of dwell of the die plunger in its downward position, and preferably a short interval thereafter, but is discontinued and the roller 280 is withdrawn prior to the next increment of movement of the mandrel 42.

Station V

After the partly finished cup, in its holder F, has been moved into axial alignment at station V (Figs. 2 and 24) the male die 177b is moved downwardly by the head 155 so as to securely hold the partially formed cup in the female die F in the manner previously described with respect to stations II and IV and the bottom squeeze plunger 320 is moved upwardly and the segments 322 are expanded to squeeze or press the interlocking bottom portions of the cup body and bottom member into intimate engagement; the advantage of this being that whereas in the rolling operation at station IV the pressure was exerted

at a limited point progressively around the periphery, at this station V substantially the entire periphery is placed under pressure at the same time. At this station cooling medium is introduced through the male die 177b in the manner identical with that previously described with respect to station II (Fig. 12).

The bottom squeeze is continued in operation until after the male die 177b commences its return movement upwardly but is withdrawn downwardly to its retracted position before the turret 42 commences its next increment of movement to station VI.

Station VI

15 After the turret has come to rest with the cup in axial alignment at station VI the male die 177c is moved downwardly in cooperative engagement with the cup and its female die in the manner previously described in connection with stations II, IV and V and cooling water is again circulated through the male die to prevent delamination. At this station a second bottom squeeze mechanism may be used if desired and in some instances such a second operation is desirable, in which event mechanism identical with that previously described in connection with station V may be employed and the squeezing head may be actuated from the same cam lever 338 (Fig. 2) previously described in connection with station V. After the head 155 has been moved upwardly on its return stroke to withdraw the male die 177c the turret 42 next moves the cup to station VII for its discharge from the female die F; the cup now being complete except for the beading of its lip, which is desirable.

Station VII.—Beading the cup lip, discharging, and stacking the completed cups

Referring more particularly to Figs. 26 and 27: 40 after the female die F has been brought to rest in axial alignment with station VII the beading die 391b moves downwardly to bring its suction head such as 391 into engagement within the cup and hold it for a dwell interval sufficient to permit suction to be imposed on the orifices such as 405. At this time the beading die ring such as 390 is disposed upwardly and is not interfered with by the upper edge of the female die F. As the suction head 405 commences its upward stroke and toward the end of its dwell period at that station the push-up head 345 is moved upwardly and as it engages the bottom of the cup compressed air is emitted from the orifices 362 to assist in releasing the cup from the female die F, so that the upward movement of the suction head 405 withdraws the cup to a horizontal position such as indicated in Fig. 27. The beading turret 370 is then rotated an increment of movement to station VIIA (Figs. 1 and 27) where it is momentarily brought to rest in axial alignment with the cup holder 429 and is then moved downwardly so as to bring the cup into the holder 429 with the upper edge of the cup extending above the beading die member 421 and into register with the groove provided in the complementary beading die ring 390. As the beading die ring 390 moves downwardly the upper marginal edge of the cup body is beaded in the manner well understood by those skilled in the art. The beading turret 370 is then moved upwardly and when it has reached its upper position is rotated an increment of movement to bring the cup into axial alignment at station VIIIB. The beading turret 370 is then moved downwardly and at the end of its downward stroke the outer end of the arm

such as 393 engages the valve head 437 to thereby admit compressed air through the hollow post 432 inwardly through the bore 431 downwardly through the passage 402 and outwardly into the interior of the cup to discharge the same: it being noted that at this time the plunger valve end 415 has engaged the stop screw 415 to close the suction passage into the bore 401. The discharged cup passes downwardly and is guided by the wire rails 444 onto the horizontal stacking rails 448 and the lip of the cup is then engaged by the stacking pusher 449 to move the cup into stacking engagement with cups previously discharged. It is noted that during the cycle of operation of the beading turret its movements are synchronized with the movements of the cup holder turret 42 so that the intervals when the beaded turret is in its uppermost position correspond to the periods during which the main turret 42 is moving.

Station VIII

After a cup has been withdrawn at station VII the empty female die F moves onto station VIII which is an idle station, and from there moves onto station I where it receives another pre-folded cup blank and commences a cycle of operation identical with that previously described.

It will be understood that as one cup is progressing through the various stages of manufacture a second is following through the identical stages so that a complete cup is being discharged for every one-eighth revolution of the main turret 42.

Having thus described my invention with particularity with reference to the preferred method of carrying out the same and in connection with the present preferred apparatus for carrying out the same, it will be obvious to those skilled in the art, after understanding my invention, that various changes and modifications may be made therein without departing from the spirit and scope of my invention, and I aim in the appended claims to cover such changes and modifications as are within the scope of the invention.

What I claim is:

1. In apparatus for making receptacle bodies from blanks of paper or the like sheet material, the combination of mechanism for prefolding said blank into approximate body form including a prefolding receptacle having a longitudinally extending fixed wall peripherally disposed about its longitudinal axis and provided with a relatively narrow longitudinally extending mouth, a feed member reciprocable toward and away from said mouth in a direction transverse said receptacle, mechanism for moving said feed member from the exterior of said receptacle through said mouth to thereby deliver a blank through said mouth and into said receptacle for folding said blank into approximate body form, and a second feed member reciprocable longitudinally of said folder for ejecting said folded blank from the lower end of said folder, a female die movable into register with said shell for receiving said folded blank, a male die having a complementary contour conforming to said female die, and mechanism for relatively moving said female and male dies into axial alignment and axially into cooperative relationship to thereby press said prefolded blank into body form.

2. In apparatus for making receptacle bodies from blanks of paper or the like sheet material, the combination of mechanism for pre-folding

said blank into approximate body form including an upright folding shell having an inwardly and downwardly tapering side wall of fixed cross-sectional contour provided with a longitudinally extending mouth and being open at its lower end, a feed member reciprocable in a direction transverse said shell, mechanism for moving said feed member into and out of said mouth to thereby insert a blank therethrough into said shell, and a second feed member reciprocable longitudinally of said shell for moving a blank along said inwardly and downwardly tapering interior to thereby fold said blank into approximate body form and eject said folded blank from the lower end of said shell, a female die movable into register with said shell for receiving said folded blank, a male die having a complementary contour conforming to said female die, and mechanism for relatively moving said female and male dies into axial alignment and axially into cooperative relationship to thereby press said pre-folded blank into body form.

3. In apparatus for making receptacle bodies from blanks of paper or the like sheet material, the combination of mechanism for pre-folding said blank into approximate body form including an upright folding shell having inwardly and downwardly tapering guide means of fixed cross-sectional contour provided with a longitudinally extending slot and an open lower end, a feed member reciprocable in a direction transverse said shell, mechanism for moving said feed member into and out of said slot to thereby insert a blank therethrough into said shell, and a second feed member reciprocable longitudinally of said shell for moving a blank along said inwardly tapering guide means to thereby fold said blank into approximate body form and eject said folded blank from the lower end of said shell, a female die movable into register with said shell for receiving said folded blank, a male die having a complementary contour conforming to said female die, and mechanism for relatively moving said female and male dies into axial alignment and axially into cooperative relationship to thereby press said pre-folded blank into final body form.

4. In apparatus for making receptacle bodies from blanks of paper or the like sheet material having a thermoplastic adhesive on a marginal edge of one end, the combination of mechanism for pre-folding said blank into approximate body form with said adhesive marginal edge disposed over the opposite end of said blank including an upright folding shell having inwardly and downwardly tapering guide means of fixed cross-sectional contour provided with a longitudinally extending slot, a feed member reciprocable in a direction transverse said shell, mechanism for moving said feed member into and out of said slot to thereby insert a blank therethrough into said shell, and a second feed member reciprocable longitudinally of said shell for moving a blank along said inwardly tapering guide means to thereby fold said blank into approximate body form and eject said folded blank from the lower end of said shell, a female die movable into register with said shell for receiving said folded blank, a male die having a complementary contour conforming to said female die, mechanism for relatively moving said female and male dies into axial alignment and axially into cooperative relationship to thereby press said pre-folded blank into final body form, and means for apply-

ing heat to soften said thermoplastic during the pressure period.

5. In apparatus for making receptacle bodies from blanks of paper or the like sheet material, the combination of a blank pre-folding receptacle having an open end and a side wall tapered inwardly toward said end provided with a mouth extending longitudinally thereof a distance substantially as great as the width of a blank to be formed and being relatively narrow in a transverse direction, guiding mechanism for locating said blank in operative register in front of said mouth, a feed member for inserting said blank through said mouth and into said receptacle, a female die, a cooperating male die, mechanism for moving said female die successively into register opposite the open end of said receptacle and then into register with said male die, mechanism operable in timed relation to the movement of said female die for feeding a folded blank from said receptacle into said female die, and mechanism for moving said male die into cooperative position within said female die so as to engage a blank therebetween and form the same into a receptacle body.

6. In apparatus for making receptacle bodies from blanks of paper or the like sheet material, the combination of a blank pre-folding receptacle having an open end and a side wall tapered inwardly toward said end provided with a mouth extending longitudinally thereof a distance substantially as great as the width of a blank to be formed and being relatively narrow in a transverse direction, guiding mechanism for locating said blank in operative register in front of said mouth, a feed member for inserting said blank through said mouth and into said receptacle, a female die, a cooperating male die, mechanism for moving said female die successively into register opposite the open end of said receptacle and then into register with said male die, mechanism operable in timed relation to the movement of said female die for feeding a folded blank from said receptacle into said female die, said receptacle having a side wall portion between said mouth and open end providing a surface of greater lateral extent than the width of said slot, a tucking finger on the inside of said wall portion in substantially vertical alignment with said mouth so constructed and arranged that a predetermined end of a blank is tucked under the opposite end as the blank is fed through the inwardly tapered end of said receptacle into said female die, and mechanism for moving said male die into cooperative position within said female die so as to engage a blank therebetween and form the same into a receptacle body.

7. In apparatus for making receptacle bodies from blanks of paper or the like sheet material, the combination of a blank pre-folding receptacle having an open end and a side wall tapered inwardly toward said end provided with a mouth extending longitudinally thereof a distance substantially as great as the width of a blank to be formed and being relatively narrow in a transverse direction, a female blanking die disposed in front of said receptacle with its die opening substantially centered relative to said slot, a cooperating male blanking die, means for bringing said cooperating dies into operative position to fashion a receptacle body blank from a strip of material fed therebetween, said dies serving also as guiding means for locating said blank in operative register in front of said mouth, a feed mem-

ber reciprocable through openings in said dies for inserting a said body blank through said mouth and into said receptacle, a female body forming die, a cooperating male body forming die, mechanism for moving said female die successively into register opposite the open end of said receptacle and then into register with said male die, mechanism operable in timed relation to the movement of said female die for feeding a folded blank from said receptacle into said female die, and mechanism for moving said male die into cooperative position within said female die so as to engage a blank therebetween and form the same into a receptacle body.

15 8. In apparatus for making receptacle bodies from blanks of paper or the like sheet material, the combination of a blank pre-folding receptacle having an open lower end and a side wall tapering inwardly toward said end provided with a mouth extending longitudinally thereof a distance substantially as great as the width of a blank to be formed and being relatively narrow in a transverse direction, a pair of cooperating die members disposed in front of said mouth for cutting body blanks in centered position relative to said mouth, mechanism for feeding strip material between said die members, actuating mechanism for said die members operable in timed relation to said strip feed, a feed member reciprocable in timed relation to said cutting dies for inserting said blank through said mouth and into said receptacle, cooperating male and female body forming dies, mechanism for moving said female die successively into register beneath the open end of said receptacle and then into register beneath said male die, mechanism operable in timed relation to the movement of said female die for feeding a folded blank downwardly through said receptacle into said female die, and mechanism for moving said male die into cooperative position within said female die so as to engage a blank therebetween and form the same into a receptacle body.

45 9. In apparatus for making a paper receptacle body from a blank having a thermoplastic marginal end zone surface, the combination of cooperating male and female die members for pressing a blank into final body form, a blank prefolding receptacle having an open end and a side wall tapered inwardly toward said end provided with a longitudinally extending slot of a length substantially as great as the width of a blank to be formed and being relatively narrow in a transverse direction, a feed member for inserting a blank through said slot and into said receptacle, means for feeding said prefolded blank axially of said receptacle and into said female die member with the thermoplastic end zone surface disposed between overlapping ends of said blank, mechanism operable in timed relation to said pre-folding mechanism for successively moving said female die into position to receive said pre-folded blank and then into cooperative position with respect to said male die, 55 mechanism for moving said cooperating die members into operative pressing position, thermal means for heating one of said die members prior to its pressure position to soften said thermoplastic, whereby said blank is pressed into final form and said blank ends adhesively joined, and means for cooling the other of said die members to thereby limit the temperature of said adhesive joint prior to the removal of said body from said female die and thereby prevent delamination of the joint.

10. In apparatus for making receptacle bodies from blanks of paper or the like sheet material, the combination of a blank prefolding receptacle having an open end and a side wall tapered inwardly toward said end provided with a mouth extending longitudinally thereof a distance substantially as great as the width of a blank to be formed and being relatively narrow in a transverse direction, said receptacle having a side wall portion between said mouth and open end providing a surface of greater lateral extent than the width of said slot, a tucking finger on the inside of said wall portion in substantially vertical alignment with said mouth so constructed and arranged that a predetermined end of a blank is tucked under the opposite end as the blank is fed through the inwardly tapered end of said receptacle, a first pusher reciprocable in a direction transverse the axis of said receptacle for feeding a body blank through said mouth and interiorly of said receptacle, a second pusher reciprocable in a direction parallel to the axis of said receptacle for feeding said blank downwardly along the converging side walls of said receptacle to thereby prefold said blank with its opposite ends overlapped in desired position, said second pusher having guide fingers slidably engaged in cooperating guideways provided in said receptacle and being movable downwardly to discharge said preformed blank from the open end of said receptacle, a body forming male die disposed transversely of said receptacle, a female die alternately movable into alignment with said receptacle and with said male die, means to supply heat to said blank, and mechanism for bringing said male and female dies into body forming relationship to thereby apply pressure to said heated body.

11. In apparatus for making receptacle bodies from blanks of paper or the like sheet material, the combination of a blank pre-folding receptacle having an open end and a side wall tapered downwardly toward said end provided with a mouth extending longitudinally thereof a distance substantially as great as the width of a blank to be formed and being relatively narrow in a transverse direction, a female blanking die vertically disposed in front of said receptacle with its die opening substantially centered relative to said slot, a cooperating male blanking die, means for bringing said cooperating dies into operative position to fashion a receptacle body blank from a strip of material fed therebetween, said dies serving also as guiding means for locating said blank in operative register in front of said mouth, said receptacle being provided with outwardly flaring lips extending from said mouth toward said female blanking die, mechanism for intermittently feeding a continuous web of cup blank material vertically between and in register with said blanking dies in timed relation to the operation thereof, a feed member reciprocable through openings in said dies for inserting a said body blank through said mouth and into said receptacle, a female body forming die, a cooperating male body forming die, mechanism for moving said female die successively into register opposite the open end of said receptacle and then into register with said male die, mechanism operable in timed relation to the movement of said female die for feeding a folded blank from said receptacle into said female die, and mechanism for moving said male die into cooperative position within said female

die so as to engage a blank therebetween and form the same into a receptacle body.

12. In apparatus for making paper receptacles comprising two pieces adhesively secured together by thermoplastic side wall and bottom seams, the combination of a turret rotatable about a vertical axis, a plurality of female dies disposed in spaced relation along a circular path concentric with said axis of rotation and rigidly secured to said turret for movement therewith, an angularly fixed mandrel head spaced above said turret and vertically reciprocable toward and away from said turret, prefolding mechanism comprising a prefolding shell in fixed position above said female dies and in alignment with said circular path, a plurality of mandrels complementary to said female dies, said mandrels being mounted on said head on respective axes parallel to the axis of said female dies and circumferentially spaced along a path in peripheral alignment with said circular path of movement with said female dies, heating means for said female dies, feed mechanism for supplying body blanks and bottom blanks to said dies, and drive mechanism constructed and arranged so as to intermittently move said female dies about their center of rotation and reciprocate said mandrels in timed cooperative relation therewith and with the body and bottom blank feed mechanism.

13. In apparatus for making paper receptacles comprising two pieces adhesively secured together by thermoplastic side wall and bottom seams, the combination of a turret rotatably mounted on a drive shaft having a vertical axis, a plurality of female dies disposed in spaced relation along a circular path concentric with said axis of rotation and rigidly secured to said turret for movement therewith, said female dies being provided with fluid jackets in communication through said shaft with a suitable heating fluid, an angularly fixed mandrel head spaced above said turret and vertically reciprocable away and toward said turret, prefolding mechanism comprising a prefolding shell in fixed position about said female dies and in alignment with said circular path, a plurality of mandrels complementary to said female dies, said mandrels being mounted on said head on respective axes parallel to the axis of said female dies and circumferentially spaced along a path in peripheral alignment with said circular path of movement with said female dies, certain of said mandrels being provided with a fluid chamber in communication with a source of cooling fluid, and drive mechanism constructed and arranged so as to intermittently move said female dies about their center of rotation and reciprocate said mandrels in timed cooperative relation therewith.

14. In apparatus for making paper receptacles comprising two pieces adhesively secured together by thermoplastic side wall and bottom seams, the combination of a turret rotatable about a vertical axis, a plurality of female dies disposed in spaced relation along a circular path concentric with said axis of rotation and rigidly secured to said turret for movement therewith, an angularly fixed mandrel head spaced above said turret and vertically reciprocable away and toward said turret, prefolding mechanism comprising a pre-folding shell in fixed position about said female dies and in alignment with said circular path, a plurality of mandrels complementary to said female dies, said mandrels being mounted on said head on respective axes parallel to the axis of said female dies and circumferentially spaced

along a path in axial and peripheral alignment with said circular path of movement with said female dies, a bottom spinning head mounted below said female dies coaxial with one of said mandrels and reciprocable into and out of cooperative association therewith, a bottom rolling head similarly mounted and cooperatively disposed relative to a succeeding one of said mandrels and a bottom squeezing head similarly mounted and cooperatively disposed relative to one of said mandrels succeeding the one cooperating with said rolling head, heating means for said female dies, feed mechanism for supplying body blanks and bottom blanks to said dies, and drive mechanism constructed and arranged so as to intermittently move said female dies about their center of rotation and reciprocate said mandrels and said bottom spinning and bottom rolling and bottom squeezing heads in timed cooperative relation therewith and with the body and bottom blank feed mechanism.

15. In apparatus for making receptacle bodies from blanks of paper and the like sheet material, the combination of a blank preforming receptacle formed with a cavity axially tapered to a relatively restricted exit end, a longitudinal slot being provided through the wall of said cavity, mechanism for supplying a succession of blanks in position to extend across said slot, a blank feeder member constructed and arranged to engage the mid-portion of the surface on each successive blank opposite said slot, mechanism for moving said feeder member through said slot into and then out of said receptacle to thereby thrust a blank in folded condition through said slot and release the blank within said receptacle with the end edges of the blank along opposite sides of said slot, plunger means movable generally axially of the receptacle for then thrusting the blank toward said restricted exit end for causing said blank edges to overlap, and mechanism for operating said plunger means in predetermined timed relation with said feeder mechanism.

16. In apparatus for making receptacle bodies from blanks of paper and the like sheet material, the combination of a blank preforming receptacle formed with a cavity axially tapered to a relatively restricted exit end, mechanism for supplying a succession of blanks in front of said receptacle and in a plane generally parallel to said receptacle axis, a blank feeder member constructed and arranged to engage the mid-portion of the surface on each successive blank opposite said axis, mechanism for moving said feeder member beyond said axis and adjacent the rear side of said receptacle to thereby position the major portion of said blank within said receptacle and release the blank within said receptacle with the end edges of the blank disposed adjacent each other and extending in relatively opposite directions, plunger means movable generally axially of

the receptacle for then thrusting the blank toward said restricted exit end for causing said blank edges to overlap, and mechanism for operating said plunger means in predetermined timed relation with said feeder mechanism.

17. In apparatus for making receptacle bodies from blanks of paper and the like sheet material, the combination of a blank preforming receptacle having a side wall tapered inwardly toward one end and provided with an elongated narrow mouth extending longitudinally thereof, blank cutting mechanism disposed in front of said mouth so as to position a cut blank transversely of said mouth with its mid-portion in register with said mouth, a blank feed member disposed on the side of the plane of said blank opposite said receptacle and having a blank engageable portion movable transversely of said blank and into said receptacle mouth for inserting said blank in folded form through said mouth and releasing the same in said receptacle, and mechanism actuating said feed member in timed relation to said blank cutting mechanism so as to feed said blank into the receptacle upon its being cut.

18. In apparatus for making receptacle bodies from blanks of paper and the like sheet material, the combination of a blank preforming receptacle having a side wall provided with an elongated narrow mouth extending longitudinally thereof, blank cutting mechanism disposed in front of said mouth so as to position a cut blank transversely of said mouth with its mid-portion in register with said mouth, a blank feed member disposed on the side of the plane of said blank opposite said receptacle and having a blank engageable portion movable transversely of said blank and into said receptacle mouth for inserting said blank in folded form through said mouth and releasing the same in said receptacle, and mechanism for actuating said fold member and blank cutting mechanism in such timed relationship that said feed member engages said blank at about the time said blank is cut and said feed member is returned to the side of the plane of said blank opposite said receptacle prior to the cutting of the succeeding blank.

JOHN HENRY BROWN, JR.
